UNITED STATES PATENT OFFICE

2,015,276

ELECTRIC CORD CONNECTER

Louis Ludwig, Brooklyn, N. Y.

Application March 27, 1934, Serial No. 717,589

2 Claims. (Cl. 173—332)

The invention relates to electric cord connectors and more particularly to the methods of manufacturing such devices. It has for its main object to provide a device of extremely simple, 5 but strong construction which can be made with very inexpensive parts and assembled with a minimum expenditure of labor. Another object is to so construct the device as to remove all danger of the wires connected with the device coming in electric contact with each other or being pulled out by severe usage.

A further object is to so construct the device as to prevent the contact blades, as well as the contact prongs, from getting out of proper 15 alignment. A still further object is to provide a device to which it is easy to attach the electric wires and which is easy to assemble or disassemble.

These and various other objects and advantages will be readily understood from the following description and from the accompanying drawing of preferred embodiments of the invention in which, however, certain modifications may be made without departing from the scope 25 of the appended claims. In the drawing

Fig. 1 is a side elevation of a cord connector made in accordance with the invention,

Fig. 2 a cross-sectional side elevation of same taken on line 2—2 of Fig. 5,

Fig. 3 another cross-sectional side elevation taken on line 3—3 of Fig. 5,

Fig. 4 a bottom view of Fig. 1,

Fig. 5 a bottom view of the cap of the cord connector,

Fig. 6 a top view of the housing of the cord connector,

Fig. 7 a plan view of a certain member used in the device, and

Fig. 8 a side elevation of a slightly modified connector.

Referring now to the drawing, the connector consists of a housing 10 and a stationary cap 11. Two bosses 12 and 13 are molded in the inside of the cap and to these bosses a yoke 14 is secured, preferably with so-called drive-screws 15. A pair of contact blades 16 and 17 are also secured to the yoke by these screws. The yoke, as well as the cap and housing, is made of insulating material, and the yoke is preferably made in the shape shown in Fig. 7.

The housing is made with an interior, concentric boss 18 and two recesses 19 and 20 in which the contact blades 16 and 17 are inserted. The cap and the housing are secured together by means of a screw 21 which passes through a hole

22 molded in the boss 18 and which is threaded in a hole 23 in the yoke 14. The bottom of the housing is provided with two rectangular holes 24 and 25, through which the prongs 26 and 27 of an attachment plug 28 will pass to contact 5 with the blades 16 and 17.

The cord 29 to which the connector is attached passes through a hole 30 in the cap 11 and the individual wires 31 and 32 of the cord are secured under the heads of the screws 33 and 34 10 in the regular manner. However, the individual wires are first drawn into the slots 35 and 36 which are formed in the yoke 14, as shown in Fig. 5. Securing the wires in this manner removes all danger of them being "shorted" and 15 also prevents them from being pulled out.

The contact blades 16 and 17, which are bent in the shape shown in Fig. 2, may be made of very light-gauge material due to the manner in which their free ends 37 and 38 abut against 20 shoulders 39 and 40 which are formed in the recesses 19 and 20. The attachment plug 28 is constructed in the same manner as the cap 11, except that the prongs 26 and 27 are substituted for the blades 16 and 17. 25

In the modification shown in Fig. 8, handle grips 41 and 42 have been added to the cap 11 and to the attachment plug 28 respectively, otherwise the construction is identical with the construction of the connector just described. 30 The handle grips make the connector very convenient to operate.

It will be seen that the yoke 14 serves several purposes in the device. It serves, in combination with the screw 21, as a means for clamping the 35 cap and the housing together; it spaces the wires 31 and 32 in such a manner as to remove all danger of "shorts" between them, at the same time relieving the strain on these wires; and, when the connectors are made of soft rubber, it 40 keeps the blades 16 and 17, as well as the prongs 26 and 27 in alignment, preventing them from being pressed into the soft rubber. While the connector illustrated in the drawing is shown as it would appear when molded from "Bakelite" 45 or similar material, when made of soft rubber, it is merely a matter of increasing the thickness of the various walls.

Having described my invention and its objects, what I claim as new and wish to protect by Letters Patent, is:

1. A cord connector comprising an insulating cap having an interior recess for electric wires and a central opening through which these wires pass, a yoke made of insulating material, 55

- a pair of contact blades having wire connecting means, said contact blades and said yoke secured to the insulating cap by the same fastening means, an insulating housing having openings in 5 one end for receiving a pair of contact prongs, recesses formed in said housing into which said contact blades fit, an opening formed axially in the housing, and a screw passed through said opening and threaded in a hole in the yoke for 10 securing the housing to the cap.
2. A cord connector comprising an insulating cap having an interior recess for electric wires and a central opening through which these wires pass, a yoke made of insulating material, a pair

of contact blades having wire connecting means, said contact blades and said yoke secured to the insulating cap by the same fastening means, an insulating housing having openings in one end for receiving a pair of contact prongs, recesses 5 formed in said housing into which said contact blades fit, an opening formed axially in the housing, a screw passed through said opening and threaded in a hole in the yoke for securing the housing to the cap, and two oppositely disposed slots formed in the yoke to separate the 10 wires connected to the contact blades.

LOUIS LUDWIG.
